[57] **ABSTRACT**

In a compressor of a movable vane type comprising a cylinder, a hollow rotor eccentrically positioned within the cylinder bore and arranged so as to be always inscribed with the cylinder bore surface on a fixed inscribing line and movable vane means radially positioned in the rotor so as to be always slidably contacted with the cylinder bore surface, said movable vane means comprises one vane of plate shape diametrically passed through and slidably supported by the rotor, said cylinder bore is defined by combination of an arc portion with one of the specified peripheral curve portions logically derived or only by the specified closed curve logically derived so that said vane, during rotation of the rotor, is always slidably contacted at its outer ends with the cylinder bore surface without being radially reciprocated; and oil reservoirs communicating to a lubricating system provided within central recesses on valve and side plates forming ends of the cylinder bore by end portions of vane slots formed on the rotor at diametrically opposite side so as to sufficiently lubricate all parts in the cylinder bore.

FIG. 5

ROTARY COMPRESSOR WITH INTEGRALLY CONNECTED, DIAMETRICALLY ALIGNED VANES

The subject invention is directed to a rotary compressor having a one-piece vane mounted in a cylinder having a bore of any one of known cross-sectional shapes specially devised for such one-piece vanes. A hollow rotor is eccentrically located within the cylinder bore and includes two diametrically opposed slots for slidably receiving the integral vane. A valve plate including outlet valves and a side plate are respectively located on opposite ends of the rotor and an oil pump for circulating lubricating oil is also provided in the housing of the compressor.

Such a compressor, if its rotor is reversely rotated, can be directly used as a vacuum pump as it is. Therefore a "compressor" in the description of the invention and the appended claims comprehends a vacuum pump.

In the conventional compressor with the one-piece vane mentioned above, lubrication of all parts within the cylinder bore is effected solely by lubricating oil jetted into the cylinder bore or on the ends of the rotor through oil ports or passages. The lubricating oil is trapped and entrained by a small space formed between the outer end of each vane and a vane slot formed in the rotor when said outer end arrives at or near its inner extent of movement. In such a lubricating system, the lubricant does not reach all parts in adequate quantities when the rotor is rotated at higher speeds in the range of 4,000 - 6,000 r.p.m. as in automobile air conditioner compressors which are subjected to a wide range of rotational speeds.

Therefore, a first object of the invention is to provide a rotary compressor having a unitary vane and new and improved lubrication means.

Another problem with prior known compressors using solid rotors arises from the necessity of having closely and smoothly slidable contact between the vane and the vane slot. It is costly and difficult to precisely finish the required slot in the solid rotor and machining of the slot having the exact same length as the breadth of the vane is also difficult to accomplish and expensive in cost.

A second object of the invention is to provide compressor means not requiring difficult and expensive machining for formation.

In order to achieve the first and second objects, the preferred embodiment of the invention is directed to a rotary compressor with a vane of one-piece including a cylinder having a bore of any one of known cross-sectional shapes specially designed for such a one-piece vane. A hollow rotor is eccentrically located within the cylinder bore so as to be rotated on a fixed axis and is provided with two diametrically opposed slots for slidably receiving the vane which extends through the rotor. Valve and side plates are located on opposite ends of the rotor respectively and an oil pump is provided for circulating oil in the compressor. The rotor is provided with an internal cavity of perfectly circular cross-sectional shape, said slots on the rotor are formed over the entire axial length of the rotor so as to open into said cavity except for end portions of the slots extending on ends of the rotor. The valve and side plates are provided with central cylindrical recesses for receiving the ends of the rotor and oil openings open into the

central cylindrical recesses adjacent the outer peripheral wall of the opening to define oil reservoirs within the central recesses. The end of the slots pass through said reservoirs during each rotation of the rotor.

In order to more clearly understand the invention, its preferable embodiment is now described in more detail with reference to accompanying drawings in which:

FIG. 1 is a longitudinal sectional view of the rotary compressor according to the invention;

FIG. 2 is a cross-sectional view taken along the line 2-2 in FIG. 1;

FIG. 3 is a cross-sectional view taken along the line 3-3 in FIG. 1;

FIG. 4 is a perspective view of the rotor; and

FIG. 5 is a perspective view of an assembly of the rotor, the vane and the valve plate showing the important features of the invention with a part of the valve plate broken off for clarity.

In FIGS. 1, 2 and 3, 1 indicates a cylinder, 3 a front

20 cylinder head, 5 a rear cylinder head, 7 a valve plate, 9 a drive shaft, 11 movable vane means, 13 a side plate, 15 a seal assembly, 17 an oil pump, 19 a connector for sucking gas (e.g., a refrigerating medium) into the compressor (a discharge connector is not shown), 21

25 and 21' indicate low pressure gas channels respectively, 23 indicates a high pressure gas channel, 25 an oil pan, 27 and 27' indicate outlet valves and 29 indicates a hollow rotor bodily formed with the drive shaft 9. Further 43, 45 and 47 indicate oil channels leading

30 from the oil pan 25 to the oil pump 17 openings 49, 51 and 53 are oil channels leading from the oil pump 17 to contacting surfaces between the cylinder bore and the rotor 29 and to the seal assembly 15. Member 55 indicates a return oil channel leading from the seal assembly 15 to the oil pan 25.

As shown in FIGS. 3 and 4, the hollow rotor 29 has a cavity 39 a cross-sectional shape of which is circular. The cavity 39 is formed by a suitable tool through a

40 driving aperture 65 provided on the drive shaft 9 for a drive pin 63 of the oil pump 17 (see FIG. 1). The hollow rotor 39 is provided with two diametrically opposed vane slots 35 which extend over the entire axial length of the rotor and open into the cavity 39 except for the end wall portions of the slots. Thus, the vane

45 slots 35 may be very precisely finished by a broach simultaneously passing through them. As shown in FIG. 1, the valve and side plates 7 and 13 are respectively provided with central recesses 41 and 41' of cylindrical shape for receiving the ends of the rotor 29 and oil

50 openings 61 and 61' for supplying the lubricating oil by the oil pump 17 through the oil channels 51 and 53 into oil reservoirs 57 and 57' as described later on with reference to FIG. 5. The oil openings 61 and 61' are preferably located near the fixed inscribing line, but may be located in any position other than said line provided that said oil openings are connected to any one of the oil channels. The outer edge of vane 11 includes two elongated seal apices 31 of small mass which extend

55 axially of the cylinder and contact the surface 1a of the cylinder bore. Each apex 31 is telescopically seated in each slot 37 formed axially of the cylinder on the outer ends of the vane and urged toward the cylinder bore surface 1a by a relatively weak spring 33 located on the bottom of each slot 37 and also compensating wear of the seal apex. Alternatively, said seal apices may be urged by hydraulic means (not shown) in lieu of springs 33.

Referring to FIG. 5, there is shown, in more detail, the important feature according to the invention. In order to clarify this figure, the side plate 13 is omitted from FIG. 5; however, its construction is substantially the same as that of the valve plate 7.

When one end of the rotor is assembled in the central recess 41, it will be seen that small spaces, i.e., two diametrically opposed oil reservoirs 57 (only one of them is shown) are defined within the central recess 41, adjacent to the peripheral side wall 42 thereof, by the rear end surface 12 of the vane and the rear end portions 36 (only one of them is shown) of the slots 35 extending on the rear end of the rotor and not opened into the cavity 39.

When the rotor is rotated, each reservoir 57 is displaced along the peripheral side wall 42 and fed with the lubricating oil through the oil opening 61 provided on the valve plate 7, when said oil opening opens into and communicates with the oil reservoir 57, during each rotation of the rotor as the reservoir 57 moves past opening 61. Corresponding reservoirs 57' are provided on the opposite end of the rotor for communication with opening 61' once during each revolution of the rotor.

The invention has substantial advantages over the prior known devices in that the oil reservoirs 57 and 57' are rotated with the rotor so that effective lubrication of all parts is achieved. For example, contacting surfaces between the valve and side plates with the ends of the rotor, the vane and said plates and the slots in the rotor and said vane, and the slots for the seal apexes 31, as well as contacting surfaces between the rotor and the cylinder bore on the fixed inscribing line and said bore and the outer ends of the vane, are all effectively lubricated.

Since the hollow rotor has a perfectly circular cross-sectional cavity 39, the precise machining of the slots for the vane is very easily completed as compared with the difficult machining required for a solid rotor; more-

over, the present invention largely avoids the risk of static and dynamic unbalance of the rotor itself.

Moreover, since the slots for the vane are machined over the entire axial length of the rotor, their machining is also easy to accomplish as compared with the conventional slots having the same exact length as the breadth of the vane, i.e., not extending over the entire axial length of the rotor.

What is claimed is:

10. A rotary compressor comprising, a unitary one-piece vane, a cylinder having a bore, a hollow rotor eccentrically mounted for rotation within said cylinder bore including two diametrically opposed slots, said vane being slidably received in said slots, a valve plate 15 and a side plate respectively mounted on opposite ends of the cylinder adjacent opposite ends of the rotor, an oil pump for circulating lubricating oil in the compressor, wherein said rotor includes a hollow internal cavity, said diametrically opposed slots of the rotor are 20 formed over the entire axial length of the rotor so as to open into said cavity except for end portions of the slots, and said valve and side plates each include inwardly facing central cylindrical recesses defined by an end wall and a peripheral cylindrical wall which recesses matingly receive the opposite ends of the rotor and oil injection openings connected to conduit means extending from said oil pump and extending into said central recesses adjacent the peripheral walls thereof whereby oil reservoirs are wholly contained within said 25 central recesses, said oil reservoirs being defined by the peripheral wall of the recess, end surface of the vane, and side and bottom walls of said slots so that said reservoirs are placed in communication with said oil injection openings once during each revolution of said rotor 30 to effect the supply of oil into the oil reservoirs by the oil pump.
2. The invention of claim 1 wherein said hollow internal cavity is of circular cross-sectional shape.
